UNITED STATES PATENT OFFICE.

ALFRED BREDENBERG, OF CHAMPLAIN, NEW YORK, ASSIGNOR OF ONE-HALF TO THE SHERIDAN IRON WORKS, A CORPORATION OF NEW YORK, AND ONE-HALF TO T. W. & C. B. SHERIDAN COMPANY, A CORPORATION OF NEW YORK.

EMBOSSING-PRESS.

No. 821,079.

Specification of Letters Patent.

Patented May 22, 1906.

Application filed August 20, 1904. Serial No. 221,570.

To all whom it may concern:

Be it known that I, ALFRED BREDENBERG, a citizen of the United States, and a resident of Champlain, Clinton county, New York, have invented certain new and useful Improvements in Embossing-Presses, of which the following is a specification.

My invention relates to embossing-presses, and more particularly to such presses as are used by bookbinders for embossing and similar work requiring great pressure.

Machines of the class referred to have a stationary head or member, a movable head or member, and power mechanism for operating the movable head.

My invention has for an object to provide an improved power mechanism for such presses whereby the movable head may be quickly operated with the required force and with a minimum expenditure of power; also, to provide a power mechanism which will operate the movable head with uniformity and without subjecting the same to lateral forces, whereby accuracy and precision in the operation of the machine are obtained; also, to provide a power mechanism which is simple and compact in construction and at the same time powerful and efficient in operation.

These and other objects of the invention will more fully appear from the following description.

My invention consists in the novel parts, improvements, and combinations herein shown and described.

The accompanying drawings, which are referred to herein and form a part hereof, illustrate one embodiment of my invention and serve, in connection with the description herein, to explain the principles thereof.

Of the drawings, Figure 1 is a side elevation of an embossing-press constructed in accordance with my invention. Fig. 2 is an end elevation of the same, as seen from the left in Fig. 1; and Fig. 3 is a vertical longitudinal section of the same.

An embossing-press constructed in accordance with certain features of my invention comprises a stationary head, a movable head, mechanism including members moving in opposite directions transversely to the line of movement of said movable head for operating said head, a toggle device for moving said members, power mechanism for operating

said toggle device, said power mechanism including a shaft and connections between said shaft and said toggle device constructed to cause a quicker movement of the movable head through the greater part of its stroke and a slow powerful movement at the end of its stroke, and means independent of said power mechanism for controlling the action of said toggle device upon said oppositely-moving members.

In accordance with the best embodiment of the invention and as illustrated in the accompanying drawings the machine is provided with a suitable base 1, a stationary head 2, connected to said base by the pairs of tension-rods 3 and 4, and a movable head 5, guided to move vertically between the tension-rods. For the purpose of guiding the movable head 5 accurately guide-blocks 6 and 7 are preferably secured rigidly to the pairs of tension-rods 3 and 4, respectively, said guide-blocks being provided with ways in which elongated bearings of the head 5 are accurately fitted.

The transversely-movable members for operating the movable head may be of any suitable construction. In accordance with the best embodiment of the invention and as illustrated in the drawings said members are in the form of toggles 8 and 9, said toggles being suitably seated on the base 1 and arranged to engage the movable head 5 near its opposite ends. Preferably the distance between the bases of said toggles is slightly greater than the distance between the upper ends of the same, and said toggles are constructed to move inwardly to lower the head 5 and outwardly to force the same upwardly. Any suitable device may be employed for moving the toggle members in opposite directions as required to cause them to properly operate the movable member of the press. In accordance with the best construction and as shown a toggle device consisting of the links 10 and 11 is employed, said links being pivotally connected together at their inner ends and pivotally connected at their outer ends to the toggles 8 and 9, preferably, by inwardly-offset lugs formed on the lower members of the toggles 8 and 9, as shown.

In accordance with one feature of my invention the device for operating the toggles 8 and 9 is positively controlled in its action by means

independent of the power device, whereby accuracy and precision in the operation of the toggles 8 and 9 is insured and at the same time all undue strain is taken off from the power mechanism. As shown, the pivot-pin 12, by which the toggle members 10 and 11 are connected to each other, is positively guided to move in a vertical direction by means of the vertical guideways formed in the brackets 13 and 14, secured at opposite sides of the base 1, so that the action of the toggle device 10 and 11 upon the toggles 8 and 9 is positively controlled and both toggles 8 and 9 are caused to move in exact unison and to exactly the same extent.

Any suitable means adapted to cause a quick movement of the movable head through the greater part of its stroke and a slow powerful movement of the head at the end of its stroke may be provided for operating the toggle device 10 and 11. In accordance with the best construction, and as shown a cam 16 is provided for this purpose, said cam being mounted upon a transverse shaft 17, solidly journaled on opposite sides of said cam in the base 1. An antifriction-roller 18 is preferably mounted upon the pin 12 of the toggle device and serves to communicate the motion of the cam to said toggle device with a minimum of friction and also to insure free movement of the pin 12 and the guides 13 and 14 independently of the operation of the cam.

The cam-shaft 17 may be driven in any suitable manner. Preferably, however, and as shown it is driven by power mechanism compactly mounted on the base 1 of the machine, the same consisting of a large gear 19, secured to one end of the shaft 17 and arranged to mesh with a pinion 20, fixed to one end of a counter-shaft 21, journaled in the base 1, and provided at its opposite end with a large driving-gear 22. As shown, the gear 22 is driven by a pinion 23, fixed to one member of a clutch 25, mounted upon a power-shaft 26, journaled in brackets 27, secured at one end of the base 1. The power-shaft may be driven in any suitable way, as by belt-pulley 28, a fly-wheel 29 preferably being provided to insure the uniform and powerful operation of the members. The clutch 25 may be operated in any suitable way, as by an arm 30, fixed to one end of a shaft 31, which extends through the base 1 from the rear to the front of the machine, where it is provided with a pair of foot-levers 32.

It will be seen that as the cam 16 is rotated the toggle device 10 and 11 will be moved upwardly in the guides 14 and 15, and thereby straightened, so as to force the toggle members 8 and 9 outwardly, and thus lift the movable member 5 of the press. A double-toggle action is thus produced which is very powerful, and at the same time the mechanism is precise and positive in action and free

from friction or strains which are apt to result in loss of power. All the strains to which the toggle mechanism is subjected are practically confined between the toggles and to the power mechanism for operating the same, so that no lateral forces are applied to the movable head 5. The head 5 is thus left free to move in its guides without liability of displacement with relation to the stationary head and without undue friction or strain on the parts.

My invention in its broader aspects is not limited to the particular construction shown and described, as many changes may be made in the details thereof other than those herein suggested or indicated without departing from the main principles of the invention and without sacrificing its chief advantages.

Having thus described my invention, what I claim, and desire to secure by Letters Patent, is—

1. An embossing-press including in combination, a stationary head, a movable head, mechanism including members moving in opposite directions transversely to the line of movement of said movable head for operating said head, a toggle device for moving said members, power mechanism for actuating said toggle device, said power mechanism including a shaft and connections between said shaft and said toggle device constructed to cause a quick movement of the movable head through the greater part of its stroke and a slow powerful movement at the end of its stroke, and means independent of said power mechanism for controlling the action of said toggle device upon said oppositely-moving members.

2. An embossing-press including in combination, a stationary head, a movable head, mechanism including members moving in opposite directions transversely to the line of movement of said movable head for operating said head, a toggle device for moving said members, a cam for actuating said toggle device, said cam being constructed to cause a quick movement of the movable head through the greater part of its stroke and a slow powerful movement at the end of its stroke, and guides for positively controlling the action of said toggle device upon said transversely-moving members.

3. An embossing-press including in combination, a stationary head, a movable head, a pair of toggle members moving in opposite directions for operating said movable head, a toggle device arranged between said toggle members for moving the same, power mechanism for actuating said toggle devices, said power mechanism including a shaft and connections between said shaft and said toggle device constructed to cause a quick movement of the movable head through the greater part of its stroke and a slow powerful

- movement at the end of its stroke, and means independent of said power mechanism for controlling the action of said toggle device upon said toggle members.
5. An embossing-press including in combination, a stationary head, a movable head, a pair of toggle members moving in opposite directions for operating said movable head, a toggle device for moving said toggle members, a cam for actuating said toggle device, said cam being constructed to cause a quick movement of the movable head through the greater part of its stroke and a slow powerful movement of the head at the end of its stroke, and guides for positively controlling the action of said toggle device upon said toggle members.
- 10 5. An embossing-press including in combination, a base, a stationary head connected to said base by tension-rods, a vertically-
- movable head guided between said tension-rods, a pair of toggles located between said base and said movable head and having members arranged to move in opposite directions upwardly to operate said movable head, a toggle device arranged between said toggle members for operating the same, a cam mounted on said base below said toggle device for actuating the same, vertical guides for controlling the said toggle device, and power mechanism mounted on said base for driving said cam. 25
- 15 In testimony whereof I have signed my name to this specification in the presence of two subscribing witnesses.
- 20 ALFRED BREDENBERG.
